George W. Walker, Pleasant Ridge, Mich., assignor to Continental Radiant Glass Heating Corporation, New York, N. Y., a corporation of Michigan

Application November 1, 1948, Serial No. 149,427

Term of patent 14 years

(CL. D81—10)

To all whom it may concern:

Be it known that I, George W. Walker, a citizen of the United States, whose post office address is 46 Oakdale, Pleasant Ridge, Michigan, have invented a new, original, and ornamental Design for a Radiant Heating Panel for Wall Mounting, of which the following is a specification, reference being had to the accompanying drawing, forming a part thereof, wherein:

Figure 1 is a top plan view of a radiant heating panel for wall mounting, showing my new design;

Figure 2 is a front elevational view of the same;

Figure 3 is an end elevation of the same; and

Figure 4 is a rear elevation of the radiant heating panel.

I claim:

The ornamental design for a radiant heating panel for wall mounting, as shown.

GEORGE W. WALKER.
